UNITED STATES PATENT OFFICE

GUSTAV A. VASEL, OF PHILADELPHIA, PENNSYLVANIA

COLOR-GRINDING MACHINE

Application filed June 7, 1928. Serial No. 283,714.

My invention relates to machines for grinding materials to a very fine state, such for example as pigments which are employed in the manufacture of inks, paints and the like.

In the grinding of materials of this character it is necessary that the grinding cylinders be accurately adjusted with relation to each other and also that means be provided whereby the pressure between the cylinders may be accurately and efficiently controlled.

The general object of the invention is to provide a novel means for regulating and controlling the pressure between the grinding cylinders in the operation thereof to grind the color materials.

It also is an object of the invention to provide means of novel construction whereby exact adjustment of the rolls or cylinders with respect to each other may be effected whereby the said rolls may be held in exact and accurate parallel relation with respect to each other during operation.

Another object of the invention is to provide means whereby injury to the mechanism of the machine may be avoided in case a piece of metal or the like should be introduced in between the relatively rotating grinding cylinders.

I shall not here attempt to set forth and indicate all of the various objects and advantages incident to my invention but other objects and advantages will be referred to in or else will become apparent from the detailed description thereof which follows.

In order that the invention may be readily understood and its many practical advantages fully appreciated reference should be had to the accompanying drawings in which I have illustrated one form of a convenient embodiment of the invention.

In the drawings:

Fig. 1 is a view in sectional top plan elevation;

Fig. 2 is a transverse vertical sectional view taken along the line 2—2 of Fig. 1;

Fig. 3 is a vertical sectional view taken along the line 3—3 of Fig. 2 in alignment with the axis of one of the grinding cylinders; and

Fig. 4 is a view in side elevation of a por-

tion of the driving gear shown at the lower side of Fig. 1.

In the drawings I have shown a base or supporting member 1 having at its opposite sides upwardly extending edge or flange portions 2 upon which the side members 3 are mounted and to which they are secured by means of bolts certain of which are indicated at 4. The under sides of the respective members 3 are cut away as indicated at 5 to form spaces between the top portions of the said members and the opposing upper sides or edge portions of the upwardly extending flange-like portions 2 of the base 1.

The under sides of the top portions of each of the side members 3 are provided with grooves 10 within which are located bars 11 which are secured therein by means of screws 12 located at intervals. The upper sides or edges of the upwardly projecting or flange-like portions 2 of the base 1 likewise are provided with grooves 13 within which are located bars 14 held in place by means of screws 15.

Bearing blocks 20 and 21 are located within the spaces formed by the cut-out portions 5. The bearing blocks 21 are held in stationary position within the said spaces, being so held by the engagement of the outwardly extending projections 22 and 23 thereon which engage notches in the adjoining portions of the side members 3 and the upwardly extending flange-like portions 2. These projections 22 and 23 are shown in Fig. 2 upon one of the blocks 21. The bearing blocks 20 are provided respectively with grooves 25 and 26 in their upper and lower sides respectively, which grooves engage the bars 11 and 14 to which previous reference has been made. The bearing blocks 20 are slidable toward and from the stationary bearing blocks 21.

The intermediate or central grinding cylinder 30 is provided with trunnions 31 at its opposite ends which are journaled in ball bearing devices 32, of any known construction, mounted within the bearing blocks 21. The grinding cylinders 33 likewise are provided at their opposite ends with trunnions 34 which are rotatably supported in ball bearing devices 35 mounted within the bear-

ing blocks 20. The bearing blocks 21 being held in stationary position as before stated, it follows that the intermediate grinding cylinder 30 is held against lateral movement. 5 The cylinders 33 which are supported at their opposite ends by means of ball bearings in the bearing blocks 20 which are slideable, it follows that the said cylinders 33 may be adjusted toward and from the central or 10 intermediate cylinder 30 so as to vary the relation between the surfaces of the outer cylinders with respect to the intermediate cylinder. All of the cylinders are rotatable. Rotation thereof is adapted to be effected by 15 means of an electric motor 40 a portion only of which is shown. Any other suitable power means may be employed for driving the cylinders 30 and 33, that is, for causing rotation thereof. The power from the motor 40 is transmitted through a driving belt 41 to a 20 pulley 42 and from the latter through gearing mechanism, indicated as a whole at 43, to the cylinders 30 and 33.

The driving gears of the gear system 43 are keyed so as to have positive connection with extensions of the journals 31 and 34 previously referred to. It is desirable and practically necessary in color grinding machines that gearing means be employed between the extended trunnions at the opposite ends of the cylinders as indicated at 45. The 25 train of gearing 45 will not be described in detail except to say that the gears which are mounted upon the trunnion 31 of the cylinder 30 are positively keyed thereto and are not relatively adjustable thereon. The gears 45^a and 45^b of the gear system or chain 45 are adjustably mounted upon the extended portions of the adjoining trunnions which 30 project from the cylinders 33. The gears 45^a and 45^b may be adjusted with relation to the trunnions upon which they are mounted and held in their adjusted positions by means of the adjustable screw bolts 46 mounted in 35 ears provided upon sleeves 47 which are keyed upon and held in fixed relation with respect to the journals of the respective cylinders 33 and 34. The inner ends of the adjustable screws 46 are located upon opposite sides of 40 lugs 48 which project outwardly from the gears 45^a and 45^b respectively. It will be apparent, therefore, that by adjusting the 45^a and 45^b may be adjusted with respect to the trunnions upon which they are mounted. The 45^a and 45^b to the gear with which they cooperate and which is mounted upon the trunnion or journal of the grinding cylinder 30 that there shall be no lost motion 50 between the engaging teeth thereof. In other words, the gear teeth of the gears 45^a and 45^b should bear the same relation to the gear upon the trunnion or journal of the intermediate grinding cylinder 30 as that which

exists between the corresponding gears of the train 43.

As has been stated already the bearing blocks 20 are slidably mounted and by reason of the engagement of the grooves in the upper and lower sides of the said blocks with the guide bars 11 and 14 the said blocks are held against twisting movements and are guided along rectilinear paths. By thus holding the said blocks against twisting movements the grinding cylinders supported thereby are held or are apt to be held in more accurate parallel relation with respect to the intermediate grinding cylinder which is held against lateral movement in either direction than otherwise would be the case.

For a purpose which hereinafter will be described more fully I provide between the blocks 21 and the blocks 20 coiled springs 50 one end of each of which rests in a depression or seat 51 in a bearing block 20 while the opposite end of each of which is seated upon an adjustable disc-like head member 52 supported upon the outer end of a screw 53 which has adjustable screw threaded connection with an intermediate stationary bearing block 21. The disc-like head members 52 are provided with holes in their peripheries, as indicated, adapted to be engaged by a spanner by which they together with the screws upon which they are supported may be rotated to effect in or out adjustments thereof. Such adjustments vary the tension of the spring which may be seated against the adjusted head.

For the purpose of pressing or forcing the outer cylinders 33 toward the central intermediate cylinder I prefer to employ fluid pressure means, preferably a liquid of some kind. The fluid, of whatever character, is supplied from a source, not shown, through a pipe 60 which is connected with a cross-wise extending pipe 61 the opposite ends of which are connected to piston cylinders 62 and 63. These latter cylinders are in communication through pipes 64 and 65 with like piston cylinders 66 and 67. These piston cylinders, in the construction as illustrated, are provided upon the opposite ends of the side members 3 and are integral therewith. Their outer ends 110 are closed by means of closing discs or heads 70. The said cylinders are provided respectively with pistons 71 having inwardly extending or projecting connecting rods or plungers 72 which extend through openings 73 in the inner ends thereof. The said plungers contact at their inner ends with breaker blocks or devices 75 which devices in the construction as illustrated are of channel shape 115 in cross section. However, they may be of any other design which may be desired. The outer sides of the said breaker blocks are provided with a depression, which may be spherical, with which depression the inner 120

ends of the said plungers 72 are in contact as shown.

In the operation of the machine, if it should happen that a piece of metal should find its way between the rolls, it is likely that some part of the mechanism would be broken or otherwise injured unless some means were provided to release or relieve the pressure. The breaker blocks constitute that means. They are so designed and constructed that upon the application of a certain predetermined crushing pressure thereto they collapse. In practice they are designed and constructed so that they will collapse or break in advance of the breakage of other parts of the machinery affected in order to relieve the pressure due to the accidental presence of a piece of metal or the like between one or the other of the cylinders 33 and the intermediate cylinder.

The delivery of the fluid through the oppositely extended branches of the pipe 61 to the piston cylinders 62 and 63 is controlled by means of valves 80 and 81. These valves are illustrated as being manually operable but they may be otherwise operated and controlled. By closing these valves it will be understood that the passage of fluid to the piston cylinders 62 and 63 and to the other two cylinders is prevented. When they are open the fluid may flow to the said cylinders. Three-way valves 82 are provided in the pipe 61 as shown, which valves when adjusted to one position permit fluid to flow outwardly or away from the piston cylinders of the machine. In other words, by opening these valves or either of them adjustment of the pressure of the fluid within the pistons may be effected.

For the purpose of indicating the pressure of the fluid within the piston cylinders pressure gauges 83 are mounted upon the pipe 61 upon opposite sides of the connection of the pipe 60 therewith. The portions of the pipe 61 upon opposite sides of the connection of the pipe 60 thereof may be regarded and referred to as branch portions, one branch having connection with the piston cylinder 62 and the other having connection with the piston cylinder 63.

In the operation of the machine fluid at the required pressure is admitted to the piston cylinders 62, 63, 66 and 67. It will be apparent that the pressure in the two cylinders 62 and 66 and in the two cylinders 63 and 67 will be the same because they are directly connected by the respective pipes 64 and 65. The first thing to be determined is whether or not the cylinders 33 are in exact parallel relation to the cylinder 30. This may be done by providing a light above the cylinders and then observing the streaks of light underneath the cylinders, and if those streaks are of the same width from end to end it will be apparent that the distance between

the adjoining surfaces of the cylinders in the same from end to end.

It will be apparent that in the grinding of color substances such as pigments to the fineness desired and necessary in the production of inks and paints the adjoining surfaces of the grinding cylinders must be located in very close relation to each other, although of course not in absolute contact.

Should it happen that when a pair of piston cylinders 62 and 66 are provided with a fluid under pressure the streak of light between a cylinder 33 (which is pressed inwardly by the plungers 72 projecting from the said cylinder) and the cylinder 30 is wider at one end than at another, that will be an indication that the springs between the bearing blocks upon which the said cylinder is supported and the adjoining bearing blocks which support the cylinder 30 are of different strengths or tensions. By proper adjustment of one or the other of the springs so as to vary the tension thereof adjustment of the cylinder 33 may be effected so as to place it in exact and absolute parallel relation to the intermediate stationary grinding cylinder. Such adjustment of the cylinder 33 may be effected by increasing the tension of the intermediate spring located at that end of the cylinder which is nearer to the adjoining end of the intermediate cylinder, or such adjustment may be effected by decreasing the tension of the spring at the opposite ends of the said cylinders. After the pressure fluid has been admitted to the piston cylinders and the pressures which are desired obtained therein the valves located within the branches of the pipe 61 are closed. It may be desired that the pressure in the two couples of cylinders 62 and 66 and 63 and 67 should be different. That condition may be readily effected or brought about either by manipulating the valves 80 and 81 to control the pressures, or it may be that initially fluid may be permitted to enter the piston cylinders so as to produce the same amount of pressure in each and all of them and thereafter the three-way valve 82 manipulated to reduce the pressure in one or the other of the couples of piston cylinders.

It will be seen that by the construction as illustrated embodying my invention I have provided means whereby the relation of the adjustable cylinders 33 with respect to the intermediate cylinder may be varied and accurately controlled; and also that I have provided separate and independently acting means for controlling the pressure of the slidable cylinder actuating fluid whereby the pressure between one of the cylinders 33 and the intermediate cylinder may be different from that of the other of said cylinders 33 and the said intermediate cylinder 30. The material to be ground is introduced in known manner onto the cylinders and is discharged

therefrom onto a discharge apron 90 from which it is discharged into a suitable receiver or container.

Having thus described my invention, what I claim and desire to secure by Letters Patent is:

1. A color grinding machine, comprising a rotatable grinding cylinder supported in stationary bearings, rotatable grinding cylinders located on opposite sides of the first named cylinder, said second named cylinders being supported in slidable bearings, guide bars for guiding the said slidable bearings in their movements, fluid pressure actuated means for forcing the said slidable bearings with the grinding cylinders supported thereby toward the said stationary bearings and the grinding cylinder supported thereby, means interposed between the said fluid pressure actuated means and the said slidable bearings which is adapted to yield upon the application of excessive pressure thereto, and means interposed between the slidable and stationary bearings which is adapted to be adjusted to effect the positioning of the said cylinders in exact parallel relation with respect to each other.

2. A color grinding machine, comprising a rotatable grinding cylinder supported at its opposite ends in stationary bearings, rotatable grinding cylinders located on opposite sides of and in operative relation to the first named cylinder, the second named cylinders being mounted at their opposite ends in slid- 35 able bearings, fluid pressure actuated means which are adapted to act upon the said slid- 40 able bearings to force them toward the stationary bearings, collapsible means inter- 45 posed between the said fluid pressure actuated means and the said slidable bearings which is adapted to yield upon the application of excessive pressure thereto, means for controlling the fluid pressure action upon the said fluid actuated means, and yielding means interposed between the said slidable bearings and the said stationary bearings, and adjustable devices for adjusting the said yielding means and varying the tension thereof.

3. A color grinding machine, comprising a grinding cylinder supported at its opposite ends in stationary bearings, grinding cylinders which coact with the first named cylinder and which are supported at their opposite ends in bearings which are slidable toward and from the first named bearings, means for guiding the said slidable bearings toward and from the stationary bearings, coiled springs interposed between the slid- 55 able bearings and the stationary bearings, adjustable devices mounted upon the stationary bearings with which the inner ends of said springs are in engagement, which devices are adapted to be adjusted independently of each other to vary the tension of the said springs, fluid pressure actuated means for acting upon

the said slidable bearings to press the same toward the stationary bearings, collapsible means interposed between the said fluid pressure actuated means and the said slidable bearings, and means for controlling the pressure of the fluid upon the said fluid pressure actuated means.

4. A color grinding machine, comprising a grinding cylinder, stationary bearings by which the said cylinder is rotatably supported, grinding cylinders located upon opposite sides of said cylinder, slidable bearings by which the said last mentioned cylinders are supported, the said bearings having grooves in their opposite sides, supports for all of the said bearings, the said supports being provided with elongated guiding means projecting therefrom and engaging with the grooves in the opposite sides of the said bearings to guide the same in their movements, fluid pressure actuating means for forcing the slidable bearings toward the stationary bearings, means whereby the pressure of the said fluid as applied to the said slidable bearings may be controlled to control the pressure exerted by the cylinders carried thereby during the grinding operation, and means interposed between the slidable and the stationary bearings whereby accurate relative adjustment of the said bearings and of the cylinders carried thereby with respect to each other may be obtained.

In testimony that I claim the foregoing as my invention I have hereunto signed my name this 4th day of June, 1928.

GUSTAV A. VASEL.
